SWIMMING SUIT

Philip Bergh, Portland, Oreg., assignor to Jantzen
Knitting Mills, Portland, Oreg.

Application June 27, 1931. Serial No. 547,194

8 Claims. (Cl. 2—67)

The invention relates to improvements in swimming suits and has for its primary object the provision of an improved swimming suit which is readily adjustable to the peculiarities 5 of the form and shape of different individuals.

Another object of the invention is the provision of a swimming suit of the character indicated, especially adapted for female wear and so constructed and arranged as to be nicely adjusted to a smooth and comfortable fit to the body of the wearer.

Another object of the invention is the provision of a swimming suit of the character indicated which is capable of economical production 15 and highly efficient in use.

Other objects will appear hereinafter.

The invention consists in the combination and arrangement of parts hereinafter described and claimed.

20 The invention will be best understood by reference to the accompanying drawing forming a part of this specification, and in which

Fig. 1 is a front view of a swimming suit constructed in accordance with the invention;

25 Fig. 2 a partial rear view thereof;

Fig. 3 a partial vertical section taken substantially on line 3—3 of Fig. 2; and

30 Fig. 4 an enlarged horizontal section taken substantially on line 4—4 of Fig. 1.

The embodiment of the invention illustrated in the drawing comprises a body 10, which may be of the usual knitted material, constructed in any desired or usual manner and provided with the usual lower skirt portion 11. The said body 35 is cut or shaped quite low in the back and in the form of a wide, downwardly concave curve 12, two spaced upward extensions 13 being provided at the front, which front is cut relatively high as shown, the opposite sides of the low cut 40 back edge 12 merging smoothly and tangentially, as indicated, into the outer sides or edges of the extensions 13.

Combined shoulder straps and belt members 45 14 and 15 are secured as shown to the upper ends of the front body projections 13, and are adapted and arranged to extend thence over the shoulders of the wearer and downwardly within the back portion of the body 10, being there threaded 50 through guide loops 16 secured to the upper central rear portion of the trunks 17, diverging thence outwardly through guide openings 18 provided at opposite sides of the waist portion of the body 10, and extending thence to the front 55 of the body where they are adjustably connected

together by means of a suitable buckle member 19.

The trunk member 17 may also be of suitable knitted material and is provided with usual or desired short leg members 20. The trunk member 17 is secured by suitable stitching throughout its front portion to the front waist portion of the body 10, said stitching extending to the points 21 at each side of the body member. The entire rear portion of the trunk member 17 is 60 free of the body member 10 and is cut to be depressed at each side, curving thence upwardly and rearwardly to form the upwardly curved side edges 22 to the central rear portion where the guide loops 16 are attached, as best shown in 65 Fig. 3.

By this arrangement a construction is provided by means of which the suit may be quickly and nicely adjusted to the peculiarities of the form or figure of each individual wearer. The suit is 75 adjusted to the body of the wearer with the members 14 and 15 extending over the shoulders, through the loops 16, openings 18, and thence to the front of the body 10. By exercising slight tension on the ends of the members 14 and 15, 80 the body will be drawn upwardly at the front from the top and the trunk member will be drawn upwardly from the rear thereof to nicely adjust the suit to the body of the wearer. When so adjusted, the suit may be secured in such 85 adjusted relation by means of the buckle 19, as will be readily understood. In this manner a comfortable and smooth fitting of the body is accomplished.

In order to protect and conceal the arrangement as far as possible, suitable belt loops 23 are provided on the body 10 at each side thereof directly over the openings 18. Additional belt loops 24 are also provided at the front of the body 10 at each side, as indicated and for obvious 95 purposes.

In order to further reinforce the body at the waist portion and carry out the full belt illusion, a false belt member 25 is stitched around the rear thereof between the belt loops 23, the ends of the 100 false belt 25 being concealed and protected under said belt loops. An additional belt loop 26 is also provided at the central rear portion of the body to further augment the full belt illusion.

While I have illustrated and described the preferred form of construction for carrying the invention into effect, this is capable of variation and modification without departing from the spirit of the invention. I, therefore, do not wish to be limited to the precise details disclosed, but 105 110

desire to avail myself of such variations and modifications as fall within the scope of the appended claims.

Having thus fully described my invention, what I claim as new and desire to secure by Letters Patent is:

1. A swimming suit comprising a body member having openings at opposite sides of the waist portion thereof; a trunk member; and combined shoulder strap and belt members connected with the front portion of said body member at the top thereof, slidably connected with said trunk member at the rear thereof and having their ends passing through said openings and thence about said body.
2. A swimming suit comprising a body member having openings at opposite sides of the waist portion thereof; a trunk member attached to said body member at its front and free at its rear; and combined shoulder strap and belt members connected with the front portion of said body member at the top thereof, slidably connected with said trunk member at the rear thereof and having their ends passing through said openings and thence about said body.
3. A swimming suit comprising a body member; a trunk member within the lower portion of said body member and attached thereto at the front but free therefrom at the rear; and shoulder straps for said body member slidably connected with the rear of said trunk member.
4. A swimming suit comprising a body member having openings at opposite sides of the waist portion thereof; a trunk member within the lower portion of said body member and attached thereto at the front but free therefrom at the rear; and combined shoulder straps and belt members attached to said body member at the top of the front thereof, slidably connected with said trunk member at the rear thereof and passing thence through said openings about said body and there detachably connected together.
5. A swimming suit comprising a body member cut low in the back and provided at the front with spaced upward extensions, there being openings in opposite sides of said body at the waist portion thereof; a trunk member arranged within the lower portion of said body member, said trunk member being secured to the waist portion of said body member at the front but free therefrom at the rear; two guide loops at the top of the central rear portion of said trunk member; and combined shoulder strap and belt members

having one of their ends secured to said front extensions and extending thence over the shoulders of the wearer and downwardly within the rear of the body portion, being threaded through the guide loops at the rear of the trunk member, diverging thence through the openings in the sides of said body, and extending thence about the body.

80

6. A swimming suit comprising a body member cut low in the back and provided at the front with spaced upward extensions, there being openings in opposite sides of said body at the waist portion thereof; a trunk member arranged within the lower portion of said body member, said trunk member being secured to the waist portion of said body member at the front but free therefrom at the rear; two guide loops at the top of the central rear portion of said trunk member; combined shoulder strap and belt members having one of their ends secured to said front extensions and extending thence over the shoulders of the wearer and downwardly within the rear of the body portion, being threaded through the guide loops at the rear of the trunk member, diverging thence through the openings in the sides of said body, and extending thence about the body; belt loops on said body over the said openings therein; belt loops at the front of said body for the passage of the front ends of said combined shoulder strap and belt members; a buckle adjustably connecting the front ends of said combined shoulder strap and belt members; and a false belt member extending around the rear of said body from one of said side belt loops to the other.

85

7. A swimming suit comprising a body member having openings at opposite sides of the waist portion thereof; a trunk member enclosed and concealed within said body member and permanently attached thereto at its front; and shoulder straps attached to said body at the front and slidably connected with said trunks at the rear, the ends of said straps passing through said openings about the body in belt form.

90

8. A swimming suit comprising a body member; a trunk member enclosed and concealed within said body member; and shoulder straps attached to the body at the front, extending over the shoulders and downwardly at the rear, the ends of said straps being there slidably connected with the rear of said trunk member.
